UNITED STATES PATENT OFFICE.

WILLIAM W. WATSON, OF ROGERSVILLE, ALABAMA.

COIN-CONTROLLED OPERATING MECHANISM.

Application filed April 12, 1922. Serial No. 551,838.

To all whom it may concern:

Be it known that I, WILLIAM W. WATSON, a citizen of the United States, residing at Rogersville, in the county of Lauderdale and State of Alabama, have invented certain new and useful Improvements in a Coin-Controlled Operating Mechanism; and I do hereby declare the following to be a full, clear, and exact description of the invention, such as will enable others skilled in the art to which it appertains to make and use the same.

This invention relates to a coin-controlled operating mechanism.

One particular object is to provide a means whereby a telephone or other instrument cannot be used or operated either to transmit or receive a message without deposit or collection of a disk which may be a coin, token or the like of proper denomination or value representing a charge for its use or service.

Another important object is to provide a construction which may be readily attached to a telephone without necessitating any alteration in its structure.

A further object is to provide a mechanism having a controlling element in combination with a detent to normally prevent its actuation and to receive the disk or coin thereagainst together with means to move the coin to displace the detent from detaining engagement with the controlling element.

Additional objects and advantages will become apparent from a consideration of the description following taken in connection with accompanying drawings illustrating one operative embodiment.

In said drawings:

Figure 1 is a view in side elevation illustrating the improved mechanism in connection with a telephone;

Figure 2 is a front elevation of the parts of Figure 1 but showing the closure of the mechanism open to disclose details;

Figure 3 is a plan view of the parts of Figure 1;

Figure 4 is a vertical sectional view on the line 4-4 of Figure 2, taken on a plane passing through the deposit chute;

Figure 5 is a horizontal sectional view on the line 5-5 of Figure 2;

Figure 6 is a vertical sectional view on

the line 6-6 of Figure 1 showing the controlling elements detained, and

Figure 7 is a view similar to Figure 6 but showing a coin within the tube and the detent displaced.

Like reference characters designate like or similar parts in the different views.

In reducing the invention to practice, a suitable housing or casing is provided such as is generally designated 10, preferably having a door or closure 11 hinged thereto as at 12 and normally maintained closed by suitable lock mechanism at 13. Casing 10 is adapted to be secured in any approved manner and to any appropriate support, for instance directly to the telephone box or structure as conventionally represented at A. The usual telephone receiver is shown at B and the supporting arm or hook therefor is designated C. This supporting arm is of usual construction, adapted to move upwardly under urgency of a spring or other means in order to place the telephone parts in an operative position.

Slidable vertically in the casing 10 as through a slot at 14 in its top wall is a controlling bar or element 15 which is adapted to be connected to the support C in any suitable manner. To this end, a clip 16, of U-shape, may straddle the supporting element C loosely and be fastened pivotally to the bar 15 by means of a bolt or the like at 17. The loose connection at 16 with the hook C provides a slip joint to compensate for the swinging movement of the hook C as compared with the sliding movement of the controlling element or bar 15.

The casing 10 may have a base or rear wall at 18 and suitably secured thereto is a guide bracket 20 having a loop at 21 in which the bar 15 is directly slid able.

The sliding movement of the bar or element 15 is adapted to be controlled by a suitable disk, coin, token or the like and to this end a deposit or receiving chute is provided at 22 which at one end preferably extends above the top wall of the casing as shown. This chute is adapted to be supported or mounted in any suitable manner and by way of example a bracket 23 is secured at 24 at opposite ends to the base 18 and at 25 the said chute 22 is riveted or otherwise fastened to the bracket. Said chute 22 is open at its upper and lower ends

and at its inner edge is provided with an elongated slot as at 26.

A detent 27 is associated with the control element 15 to extend through and move in the slot 26 and at one end 28 be disposed within the chute 22 to intercept the passage of a coin or the like therethrough. The other end of the detent which is designated 29 is normally engageable with a lug 30, suitably provided on the element 15 and having an upstanding flange 31 to prevent accidental disengagement of the detent and element.

A bracket 31' may be fastened at 32 to the base 18 to which the detent 27 is pivoted at 33. Integral with the bracket 31' is a flange 34 which may be bent over as shown so as to make the bracket 31' substantially U-shaped in cross section to better guide the detent 27 and a coin or disk moving lever 35 which is also disposed on the bracket 31' and pivoted thereto as at 36. Lever 35 normally extends slightly into the slot 26 at one end and its other end extends through an enlarged slot 38 in the controlling element 15. The bracket 31 is suitably slotted as at 38 in order to permit the movement of the levers 27 and 25.

In the event the telephone is to be operated, either to receive a message or transmit a message, the receiver B is lifted as usual but the support C can not swing upwardly as is usual and necessary until the proper coin, token, disk or the like has been deposited in the chute 22. If it should be attempted to raise the control element 15 in order to release the hook C, the lug 30 will engage the detent 27 which will thus prohibit vertical movement of the controlling element to release said hook C. In order to operate the device, the coin should be deposited in the tube 22 before the receiver B is lifted from the hook C. When the coin is deposited, it strikes the end 28, swinging the lever outwardly slightly at the end 29 and downwardly and inwardly at the end 28. Such movement of the lever moves it out of the path of movement of the flange at 31. Under urgency of the spring (not shown) of the usual hook C, upon the receiver B being removed from that hook, the bar 15 will slide upwardly and due to its connection at slot 38 with the bar 15, lever 35 will be moved downwardly in the chute in contact with the coin or disk which is designated D, causing said coin by its contact with the end 28 of lever 27 to so tilt the lever 27 that the latter's free end cannot engage the lug 30 to the end that the coin will be forced past lever 27 in order to fall from the tube into the bottom of the casing from which the coins may be removed from time to time at the closure 11. After the telephone has been used, the lever B is replaced on the hook C which depresses the

controlling element 15 in a normal or reset position from which it cannot be operated until another coin, token, disk or the like is deposited into the chute 22 as will be understood.

As merely one practical embodiment has been illustrated and described, it is to be understood that changes in the details may be resorted to provided they fall within the spirit and scope of the invention as defined by appended claims.

I claim as my invention:

1. In a coin-controlled apparatus, in combination with a controlling member normally urged toward its position of operation, a bracket, a detent lever pivoted on the bracket and extending loosely through the controlling member, said lever adapted to receive a coin thereagainst to move said lever out of engaging position with said controlling member when said controlling member moves to its position of operation, means on the controlling member engageable by the detent lever to normally resist effective movement of the controlling member, and means associated with said bracket and said controlling member operable through movement of the controlling member toward said position to move a coin past said detent lever.

2. In a coin-controlled apparatus, in combination with a controlling member normally urged toward its position of operation, a bracket, a lever pivoted to said bracket and extending loosely through said controlling member, said lever being engageable with the controlling member to resist effective movement thereof, said lever adapted to receive a coin thereagainst to move said lever out of engaging position with said controlling member when said controlling member moves to its position of operation, a lever pivoted to said bracket and engageable with said coin, and the second mentioned lever extending through the controlling element whereby it will be actuated by movement of the controlling element toward said position to move the coin past the first mentioned lever.

3. In a coin-controlled apparatus, a coin chute provided with a slot, a slidable controlling element, levers operable in said slot and extending loosely through slots in said controlling element, a lug on the controlling element associated with one of said levers, the last mentioned lever adapted to have a coin deposited thereagainst through the chute in order to move the last named lever out of engaging position with said controlling member when said controlling member moves to its position of operation, and the other lever being operable against the said coin to move the coin past the other lever.

4. In a coin-controlled apparatus, a coin chute provided with a slot, a slidable con-

trolling element, levers operable in said slot and extending loosely through slots in said controlling element, a lug on the controlling element associated with one of said levers, 5 the last mentioned lever adapted to have a coin deposited thereagainst through the chute in order to move the last named lever, and the other lever being operable against the said coin to move the coin past the other 10 lever, a bracket to which said levers are

pivoted, a flange on said bracket overlapping that lever which is remote from the lug, and a guide bracket for the controlling element.

In testimony whereof I affix my signature in presence of two witnesses.

WILLIAM W. WATSON.
